US00D685958S

(12) **United States Design Patent**
Wolfson

(10) **Patent No.:** **US D685,958 S**
(45) **Date of Patent:** **** Jul. 9, 2013**

(54) **PET RESTRAINER**(76) Inventor: **Jeffery D. Wolfson**, Woodstock, GA (US)(**) Term: **14 Years**(21) Appl. No.: **29/430,869**(22) Filed: **Aug. 30, 2012**(51) **LOC (9) Cl.** **30-09**(52) **U.S. Cl.**USPC ..... **D30/154; D30/151**(58) **Field of Classification Search**

USPC D30/154, 199, 160, 151, 153; D6/608, D6/609, 613, 614, 603, 583, 588-591, 597, D6/598, 611, 601; 119/174, 850, 650, 621, 119/600, 602, 707-712, 786-788, 791, 780, 119/782, 769-771, 795, 856; D29/118; D24/207, 208, 200, 206; D7/388; 5/417; 219/759, 730, 528, 529; 426/241; 99/DIG. 14; D5/62; 607/96, 108-111, 104; 52/155, 166, 52/157, 162, 163; D28/79, 73, 76-78, 83; D3/216, 223, 271.1, 234-236, 238, 248, 205, D3/295, 301, 703.6, 203.1, 294; D11/81, D11/103; D9/600, 629; 220/4.26, 4.27; 132/286, 287, 293-307, 314-318; 206/581, 206/823, 37, 315.1, 6.1; D21/385

CLAIM

The ornamental design for a pet restrainer, as shown and described.

DESCRIPTION

FIG. 1 is a front perspective view of a pet restrainer showing my new design;

FIG. 2 is a rear perspective view thereof;

FIG. 3 is a front elevational view thereof;

FIG. 4 is a rear elevational view thereof;

FIG. 5 is a top or bottom plan view thereof; and,

FIG. 6 is a right or left side elevational view thereof.

Broken lines and portions contained within broken line are not claimed.
